COMBINED CARAFE AND CUP

Melvin Henry Levi, Kew Gardens, N. Y.

Application January 21, 1954, Serial No. 28,625

Term of patent 14 years

(Cl. D44—21)

To all whom it may concern:

Be it known that I, Melvin Henry Levi, a citizen of the United States of America, residing at Kew Gardens, in the county of Queens and State of New York, have invented a new, original, and ornamental Design for a Combined Carafe and Cup, of which the following is a specification, reference being had to the accompanying drawing forming a part hereof.

Fig. 1 is a side elevational view of a combined carafe and cup, showing my new design;

Fig. 2 is a top plan view thereof; and

Fig. 3 is a vertical sectional view of said combined carafe and cup with the cup removed.

I claim:

The ornamental design for a combined carafe and cup, as shown.
